UNITED STATES PATENT OFFICE.

ISAAC FRANCIS BURTON, OF PHILADELPHIA, PENNSYLVANIA, ASSIGNOR TO VICTOR TALKING MACHINE COMPANY, A CORPORATION OF NEW JERSEY.

SUPPORTING FRAME FOR TALKING-MACHINE MOTORS.

Original application filed May 15, 1918, Serial No. 234,809. Renewed November 16, 1922.

To all whom it may concern:

Be it known that I, ISAAC FRANCIS BURTON, a citizen of the United States, and a resident of Philadelphia, county of Philadelphia, State of Pennsylvania, have invented certain new and useful Improvements in Supporting Frames for Talking-Machine Motors, of which the following is a specification.

10 The present invention relates to a driving mechanism and a steel supporting frame therefor adapted for use in connection with sound reproducing machines. The invention has for its object to provide an improved general combination between the driving mechanism for a talking machine and a supporting frame therefor including a novel type of built up steel supporting structure so designed as to be capable of being made under efficient standardized manufacturing methods and so constructed as to permit of a novel arrangement of the entire driving mechanism relative to the supporting frame, thus forming a novel combination of means having certain advantages in securing an accurate alignment and efficient association of the driving means of a talking machine as well as providing a more rigid, durable and 20 serviceable supporting frame capable of being manufactured with a considerable saving of material and labor.

25 Other features of this invention relate to the construction of the frame per se, including the substitution of a sectional, interconnected steel frame for supporting a driving mechanism of a talking machine instead of the type of cast iron frame heretofore used whereby certain inherent 30 disadvantages in the prior forms of construction are overcome and an improved type of frame is obtained. Moreover, by constructing a steel frame made of several parts, each part may be manufactured in 35 quantities independently of the others and the several parts when thus properly made, will so accurately interfit that no aligning, reaming of openings or machining of the assembled mechanism is necessary.

Further objects of this invention are to provide a structure of this character which will more readily withstand any possible strains imposed upon the mechanism, this being accomplished by reason of the fact

that the several sections of the supporting frame are so interrelated and tied together that a possible strain received by one of the sections is transmitted to and absorbed by certain of the others rather than imposing the entire strain on one part. Moreover, there is thereby provided a frame construction which is light, strong and rigid but at the same time capable of a certain amount of deflection without breaking or 40 permanently destroying the proper alignment of any of the various parts, as the elements, being constructed of steel, for example, will resume their normal position upon the removal of any strain which might 45 be applied thereto. Furthermore, each of the several elements is replaceable if one of the same should become distorted or broken, thereby avoiding the necessity of 50 replacing the entire supporting frame in such an emergency.

Further objects of this invention are to so construct the various elements of the type of frame mechanism referred to, that the assembling of the same is greatly facilitated, each part being complete in itself, including means for securing together the several parts, thus avoiding the necessity for separate connecting means, such as bolts or nuts, with the result that the cost of 55 assembly is relatively low and, moreover, a particularly rigid supporting frame is provided which is unlikely to become loosened, and an accurate alignment of the various elements of the driving mechanism 60 for the talking machine is also insured.

Other objects of this invention, as will appear from the specification and drawings forming a part thereof, reside in the details of construction; the particular materials 65 employed; the particular shape given to the various elements; the manner in which the same are assembled; and the combination above referred to between the supporting frame and the driving mechanism as well 70 75 80 85 90 95 100 105 as the assembled relation of the elements thereof in said frame.

It is to be understood that many of the details of construction illustrated herein may be varied without departing from the essence 105 of the invention in its broader aspect, and the drawing forming a part hereof is merely illustrative of one type of construction for attaining the objects set forth, wherein Figure 1 represents a bottom plan view of a 110

driving mechanism and supporting frame constructed and arranged in accordance with this invention, while Fig. 2 is a side elevation thereof. Fig. 3 is a perspective view of the supporting frame with the driving elements and governor and other parts of the mechanism removed therefrom. Fig. 4 is a plan view of one of the frame plates employed, while Fig. 5 is a similar view of part of a tie plate used. Fig. 6 is a sectional view partly in elevation showing the method in which the bearings are assembled to the plates of the supporting frame construction.

The type of driving mechanism illustrated herein includes a motor or driving element, a transmission mechanism to the turntable of the talking machine and a speed regulating mechanism including a governor and a regulator. The supporting frame which I have provided for the driving mechanism, while having certain inherent novel characteristics of its own, as suggested above, is also arranged to form a combination with the driving mechanism employed by reason of the fact that the entire driving mechanism includes, as a part thereof, a plurality of shafts located at a certain angle one with relation to another and the frame, by reason of its construction, is adapted to form a unitary supporting means for the mechanism and form bearings for said angularly arranged shafts. Thus in Fig. 1 there is illustrated a spring motor supported on a horizontal motor or power shaft 10 and including a plurality of spring barrels or power elements 11 and 12 adapted, when stored with energy, to drive the gear 13. The turntable spindle 14 is arranged at an angle to the shaft 10 and may be driven by the gear 13 on the shaft 10, by means of the worm 15 on the spindle 14. In the particular form illustrated there is thus a direct rectangular drive between the motor or power shaft and turntable spindle. The speed of the rotation of the spindle 14 is controlled by a governor 16, the governor being driven from the spindle 14 by gear 17 meshing with a worm 18, for example, on the governor shaft 19. In the type illustrated, the governor shaft 19 is located at right angles to the spindle 14 and parallel with the motor or power shaft 10 although it is apparent that the shaft 19 could be located in an inclined position, if desired, and moreover, the motor or power shaft 10 need not necessarily be located horizontally, but might be arranged in an inclined position. It will be therefore seen that in the type of motor employed there is an angular drive between the motor shaft and the spindle and between the spindle and the governor. Moreover, the governor regulator 20, in the type employed herewith, includes a rotatable shaft 21 carrying a pad

22 to engage the governor disk 23, the shaft 21 being located for convenience of arrangement and construction at an angle to the governor shaft 19 and has an arm 24 extending laterally therefrom and provided with ledge 25 with which the thumb screw 26 engages to adjust the arm 24 and rod 21 and control the position of the pad 22. It will thus be seen that these elements constitute an efficient, compact driving mechanism for actuating the turntable of a talking machine and that the supporting frame disclosed herein is particularly adapted therefor, certain elements of the frame being constructed to serve both as a part of the built up sectional frame and as means to support certain parts of the driving mechanism, this result being due both to the improved type of frame and to its use with the general type of driving mechanism just described.

One form of frame adapted to perform these functions, as well as having certain inherent advantages of its own—such as in its method of manufacture, construction and use in operation—is illustrated in Fig. 3 and shown in Figs. 1 and 2 with the driving mechanism supported therein. Generally speaking, the type of built up steel frame which I have designed includes a plurality of frame plates 30, 31 and 32 and a plurality of tie plates 33, 34, 35 and 36, the frame plates being adapted to support the power elements through the shaft 10, while certain of the tie plates support the turntable spindle 14 and regulating rod 21. The governor 16 likewise may be supported by certain of the frame plates which support the motor or power shaft 10. These frame plates and tie plates are formed of steel and may be readily punched out by a suitable punching press, each plate being so shaped as to properly support the various elements of the driving mechanism for the talking machine just referred to, being provided with proper openings for bearings for this purpose, and at the same time so constructed as to be secured to the adjacent plates without the use of tie bolts or nuts. One of the frame plates 32 is illustrated in Fig. 4 where it will be seen that the same is provided with certain lugs or extensions 37 adapted to extend into corresponding openings 38 in the several tie plates, one of which is illustrated in Fig. 5, the lugs 37 being headed over to tie the frames and plates together. Each of the other frame plates and tie plates are correspondingly shaped and provided with the necessary openings to receive the bearing bushings for the shafts which they support. Thus the plate 32 is provided with two openings 39 and 40, the opening 39 adapted to receive the bearing hub 41 for supporting one end of the motor or power shaft 10 while the open-

ing 40 receives the bearing bushing 42 of the winding shaft 43. As a part of this invention, the various bushings forming the bearings for the shafts of the driving mechanism, such as the bushings 41 and 42, are of such a type as may be turned out on automatic machines and when inserted into their receiving openings in the frame plates and tie plates, the same may be staked or spun over to securely position the bushings therein. This method of construction is illustrated in Fig. 6 wherein it will be seen that the bushings 41 has been secured to the plate 32 by spinning over an edge 44 to grip the plate 32 between a shoulder 45 on the bushings 41 and the spun over flange 44. It is apparent, however, that various other means could be readily employed for accurately positioning the bearing bushings 20 into the frame plates. By constructing the frame plates, tie plates and bearing bushings as set forth, each of these several elements of the supporting frame is preformed complete in itself and may be independently made with reference to the others and when assembled each part will accurately and properly interfit as intended, thus insuring the accurate construction of the frame and an accurate alignment of the 30 bearings without necessitating any later adjustment or machining of parts or other operation upon the completed frame.

The particular location and arrangement of the several bearings necessarily corresponds with the type of motor and driving mechanism for which the supporting frame is designed. In the type shown, the frame plates 30 and 31 are provided with bushings 48 and 49 which align with the bushing 41 to support the motor shaft 10, the shaft being thus supported at its ends and near its middle. Moreover, each of the frame plates 30 and 31 is provided with aligned bushings 50 and 51 for supporting the governor shaft 19. The tie plates 34 and 36 are provided with similarly constructed and positioned bearing bushings 52 and 53 for the spindle 14, while the tie plate 35 is provided with the extended bushing 54 for supporting the shaft 21 of the governor speed regulating attachment. It will thus be seen that the correlated frame plates and tie plates form a supporting frame made of punched out, built up steel 50 sections, tied together and interrelated in the manner illustrated, thereby providing a strong, relatively light supporting frame of maximum strength with a minimum amount of material with other advantages in increased efficiency in manufacture of the separate elements and the assembly of the same. It is also apparent that by reason of the particular construction employed, certain of the frame plates perform the function of 60 supporting the motor shaft and governor

shaft, for example, while the tie plates, by their particular construction and the construction or type of motor with which they are employed, operate to perform a double function of tying the frame plates together 70 and forming an accurate support for the talking machine spindle or governor regulating arm, or in other words, all of the essential driving elements of the mechanism are properly supported directly on certain 75 frame parts, and in this manner no special means is necessary for supporting the mechanism in the frame.

To position the frame and mechanism in a talking machine, the supporting frame 80 is provided with a three-point suspension in the ears 60, 61 and 62 by which the mechanism may be secured to the motor board 63, shown in Fig. 2. For this purpose there may be employed a plurality of bolts 64 85 passing through the motor board and the supporting ears and, if desired, a sound insulating washer 65 may be interposed between the motor board and the supporting ears.

In Fig. 1 there is illustrated at 70 a speed indicator which is also carried by the supporting frame and operatively associated with the governor 16. One type of indicator includes a pointer 71 adapted to move 95 over a scale on the motor board to indicate the speed of rotation of the turntable. This indicator 70 is carried by a supporting plate 72 which is secured to the tie plate 35 by set screws 73. The indicator 70 is provided with an arm 74 adapted to engage the governor disk 23 and be moved thereby as the same moves longitudinally on the governor shaft. The movement of the arm 74 is transmitted to the pointer 71 by any suitable 105 transmission mechanism. Attention is called to the fact that the tie plate 35 is of such shape as to form a suitable support for the plate 72 of the indicator 70.

From the foregoing description, it is believed that this invention will be understood without a further detailed description of its operation. It will be seen that the sectional, built up steel frame which I have provided forms the unitary supporting 110 means for the driving mechanism of the talking machine and at the same time substantially all the essential elements of the driving mechanism are directly supported by certain parts of the frame, thus avoiding the necessity for any special supporting means for any of the elements of the driving mechanism. It will be further understood that by reason of the construction described, the frame itself has many inherent advantages hereinbefore more fully pointed out. The several parts may be readily manufactured by machines and turned out in large quantities independently 120 of the other and when assembled are so 130

4
accurately made that the completed frame requires no additional manipulation to form an accurate support for the mechanism described. Furthermore, attention is called 5 to the fact that each of the parts of the frame are so shaped that they may be punched out, if desired, and no pressed steel or shaped sections are necessary, this feature being of material value in reducing 10 the cost of manufacture and facilitating the employment of standardized manufacturing methods as well as producing a simplified type of construction. Moreover, the several sections of the frame are provided 15 with integral tying means for joining each section one with the other, resulting in the rigid construction referred to, and the construction as a whole forms one efficient means for attaining the objects set forth in 20 the statement of the invention, but it is apparent that certain of the details may be altered and many modifications of the precise structure made without departing from the spirit and scope of my invention as set 25 forth in the appended claims.

Attention is called to the fact that this invention is intended to cover various other types of motors than that illustrated in the drawing, for example a single barrel 12 may 30 be used for housing a suitable spring mechanism for driving the turntable spindle 14 in which case the barrel 11 would not be used and the end frame plate 32 would also be omitted. Furthermore, it is apparent 35 that a single spring or three spring motor could be used as well as a two spring motor or four spring motor, the four spring being the type illustrated in the drawings.

Having thus described my invention, I 40 claim and desire to protect by Letters Patent of the United States:

1. In a talking machine driving mechanism having a power element, a power shaft therefor and a driven shaft located at an 45 angle relative to said power shaft, the combination of a supporting frame therefor including a plurality of frame plates for supporting said power shaft and a plurality of tie plates for joining said frame plates and supporting said driven shaft.

2. In a talking machine driving mechanism comprising a power shaft and a turntable spindle located at an angle relative to said power shaft, the combination of a 55 unitary supporting frame therefor comprising a plurality of frame plates for supporting said power shaft and a plurality of tie plates adapted to perform the two fold function of securing said frame plates together and supporting the turntable spindle.

3. In a talking machine driving mechanism comprising a power element, a power shaft, a turntable spindle located at an 60 angle relative to said power shaft and a governor, the combination of a supporting

frame for said mechanism including a plate for joining said frame plates and power shaft and said governor and a tie plate for joining said frame plates and supporting said turntable spindle. 70

4. In a supporting frame for a driving mechanism, the combination of a plurality of sheet metal frame plates and a plurality of tie plates for joining said frame plates and means whereby one of said tie plates is arranged to support a shaft driven by the power shaft of said driving mechanism, and located at an angle to said power shaft. 75

5. In a supporting frame for talking machine driving mechanisms, the combination of a set of frame plates and a set of tie plates connecting said frame plates and means integral with one of said sets of plates for joining together said frame and tie plates. 80

6. In a supporting frame for talking machine driving mechanisms, the combination of a plurality of punched out steel frame plates provided with projecting lugs and a plurality of punched out tie plates provided with openings therein to receive said projecting lugs and tie said frame plates and tie plates together. 85

7. In a supporting means for a talking machine driving mechanism, the combination of a plurality of punched out frame plates and tie plates, means for securing said frame and tie plates together and a plurality of preformed bearings positioned in said plates, said plates and bearings being separately constructed to accurately join in proper alignment and form a completed unitary supporting frame of the character specified. 95

8. In a talking machine driving mechanism comprising a power element, a power shaft, a governor, a governor shaft and a turntable spindle driven from said power shaft, the combination of a supporting frame therefor including a plurality of frame plates, one located at each end of said power shaft and one adjacent the central portion thereof, tie plates for connecting said frame plates and means whereby one of said end plates and said central plate support said governor shaft. 100

9. In a supporting frame for a driving mechanism, the combination of a plurality of frame plates and a plurality of tie plates for joining said frame plates and means cooperative with one of said tie plates for supporting a shaft driven from the power shaft of said driving mechanism, and located at an angle to said power shaft. 110

10. In a supporting frame for a driving mechanism, the combination of an upper plate, a plurality of plates rigidly secured to and depending therefrom, a tie plate rigidly joining said depending plates adjacent their lower ends, and means cooperative with said tie plate for supporting a shaft 125

driven from the power shaft of said driving mechanism, and located at an angle to said power shaft.

11. In a supporting frame for a motor the combination of an upper plate, a plurality of parallel plates rigidly secured at one end thereto and extending at right angles to said upper plate and a tie plate rigidly joining together said parallel plates adjacent their opposite ends, alined shaft bearings in said

parallel plates and a pair of alined bearings, one in said top plate and the other in said tie plate, the axis of said bearings in said parallel plates and the axis of said bearings in said top and tie plates being in planes 15 disposed at right angles to each other.

In witness whereof, I have hereunto set my hand this 13th day of May, A. D. 1918.

ISAAC FRANCIS BURTON.

Certificate of Correction.

It is hereby certified that in Letters Patent No. 1,460,406, granted July 3, 1923, upon the application of Isaac Francis Burton, of Philadelphia, Pennsylvania, for an improvement in "Supporting Frames for Talking-Machine Motors," errors appear in the printed specification requiring correction as follows: Page 2, line 101, for the misspelled word "turnable" read *turntable*; page 4, line 43, claim 1, for the word "having" read *comprising*; same page, claim 3, strike out line 67 and insert instead the syllable and words *rality of frame plates for supporting said*; and that the said Letters Patent should be read with these corrections therein that the same may conform to the record of the case in the Patent Office.

Signed and sealed this 31st day of July, A. D., 1923.

[SEAL.]

KARL FENNING,
Acting Commissioner of Patents.
